STOPPING MEANS FOR WEFT REPLENISHING LOOMS

Victor F. Sepavich, Worcester, Mass., assignor to
Crompton & Knowles Loom Works, Worcester,
Mass., a corporation of Massachusetts

Application March 18, 1946, Serial No. 655,104

7 Claims. (Cl. 139—290)

1

This invention relates to improvements in weft replenishing looms and it is the general object of the invention to provide simple and effective means for stopping the loom in the event that a shuttle is improperly placed for transfer on a weft replenishing beat of the loom.

Weft replenishing looms ordinarily employ a transerrer arm which on the replenishing beat of the loom moves downwardly to insert a fresh bobbin into the depleted shuttle. The transerrer arm and bobbin move along a fixed path, but the shuttle may come to rest at the end of the lay placed either for a proper transfer or misplaced sufficiently to interfere with correct movement of the fresh bobbin into the shuttle. Shuttle position detectors are ordinarily used to revoke transfer if the shuttle is misplaced, but these detectors do not always operate if the shuttle is only slightly misplaced.

It is an important object of my present invention to provide a shuttle position detector with an electric switch which will be closed by a misplaced shuttle on a transferring beat of the loom and thereby effect actuation of an electro-magnetic device for initiating loom stoppage.

It is another object of my invention to provide a shuttle position detector with a self-contained normally open electric switch unit which is closed by a misplaced shuttle but reopens automatically without requiring additional mechanism or movement of the detector. The switch is preferably inclosed to reduce fire hazard to a minimum.

With these and other objects in view which will appear as the description proceeds, my invention resides in the combination and arrangements of parts hereinafter described and set forth.

In the accompanying drawings, wherein two forms of the invention are shown,

Fig. 1 is a side elevation of the preferred form of my invention and part of the weft replenishing mechanism set for a replenishing operation and indicating the lay in cross section,

Fig. 2 is a front elevation of the shuttle position detector and shuttle looking in the direction of arrow 2, Fig. 1 showing the shuttle properly placed in full lines and improperly placed in dotted lines,

Fig. 3 is an enlarged side elevation looking in the direction of arrow 3, Fig. 2, showing the manner in which a misplaced shuttle closes the switch on the shuttle position detector,

Fig. 4 is a vertical section through the switch mechanism mounted on the shuttle position detector,

2

Fig. 5 is a diagrammatic view showing the electric circuit by which the switch on the shuttle position detector initiates loom stoppage, and

Fig. 6 is a view similar to Fig. 3 on a reduced scale showing a modified form of the invention.

Referring particularly to Fig. 1, the loom frame 10 supports a weft replenishing mechanism 11 which in the present instance may be of the stationary four-cell type. This mechanism has vertical bobbin delivery controlling slides 12 and a transerrer arm 13 pivoted as at 14 to the magazine foot 15. A transfer latch 16 is pivoted as at 17 to the transerrer arm and is normally down from the position shown in Fig. 1, but is raised to transfer position as set forth in Fig. 1 by a vertically extending rod 18. The latter is ordinarily down but when a replenishing operation is called rod 18 is raised to lift the latch 16 into the path of a bunter 19 on the lay 20. Prior to arrival of the shuttle S at the magazine side of the loom a bobbin designated at B will have been released from the magazine by one or another of the vertical slides 12 and be in the transfer position shown in Fig. 1 under the transerrer arm. As the lay advances the bunter 19 engages the latch 16 and rocks the transerrer arm 13 in a counter-clockwise direction as viewed in Fig. 1 to move the bobbin B downwardly into the shuttle S. The transerrer arm and bobbin move in a fixed vertical path but the shuttle moves across the lay and can assume different positions relatively to the path of the descending bobbin in certain of which it is not properly placed for transfer. It is desirable to prevent transfer if the shuttle is not properly positioned to receive the bobbin B.

It has been customary in the past to employ shuttle position detectors for the purpose of revoking operation of the transerrer arm if the shuttle is too widely misplaced. Part of such mechanism is shown in Fig. 1 and includes the shuttle position detector member or detector D which is secured by bolt 25 to a detector holder 26 pivoted to the magazine as at 21. An upwardly extending rod 28 is pivoted as at 29 to the holder 26 and is normally in raised position so that the detector D is above the path of the shuttle as the lay swings back and forth on non-transferring beats of the loom. When a transfer operation is called rod 28 moves downwardly as rod 18 rises and the detector D is lowered to the position shown in Fig. 1.

The detector D has a shank 35 by means of which it may be bolted to the holder 26 and has also a downwardly extending arm 36 terminating

in an upwardly and forwardly extending projection 37. The under surface of the detector D is rounded as at 38 and is engaged by the shuttle if the latter is misplaced on a replenishing operation, or if the shuttle is properly placed surface or edge 38 will be engaged by a vertical wall 39 carried by the lay behind the shuttle S. This latter engagement will occur later in the forward beat of the lay than shuttle engagement and is the usual means by which the detector D is raised and the magazine reset.

The matter thus far described is of common construction in multicolor weft replenishing looms and of itself forms no part of my present invention except for the changes which I have made in the shuttle position detector as set forth hereinafter.

In carrying my invention into effect I provide a shuttle engaging lever 45 pivoted at 46 to the detector D and having a lower arm 47 normally projecting slightly below the surface 38. The upper arm 48 of lever 45 is provided with a lateral stud 49 which overhangs a lever 50 forming part of an inclosed electric switch unit designated generally at E. Lever 50 is preferably resilient though not necessarily so and swings about a pivot 51 on the switch unit E. A stop finger 52 extending to the left of pivot 51 is provided to engage the unit E to limit upward movement of the lever 50 as viewed more particularly in Fig. 4. A horn 53 on detector D limits swinging movement of arm 48 to the right, see Fig. 3.

The switch unit E is of a known commercial type and includes an inclosed casing or box-like structure 55 made preferably of electric insulating material and having a top 56 in which a plunger 57 is slidably mounted. This plunger rests on a sheet metal spring 58 anchored or otherwise secured to the casing 55 as at 54. Spring 58 tends normally to remain in an up position and causes plunger 57 to maintain the lever 50 normally in the raised position shown in Fig. 4, and holds lever 45 in its normal position.

Spring 58 is curved downwardly as at 60 and is attached to a flat semi-circular spring 61 as at 62. Spring 61 is attached as at 63 to a flat snap spring 64 secured to an electrode 65 which is held between parts of the casing 55. A spring electrode 66 insulated from the electrode 65 extends into the casing and has a contact button 67 for engagement with a second contact button 68 on the snap spring 64.

The parts within the spring casing 55 are normally in the position shown in Fig. 4, but when lever 50 is depressed plunger 57 will bend spring 58 downwardly and cause the connection 62 between springs 58 and 61 to be lowered in such manner as to cause compression of spring 61. After the connection 62 has reached a given position in its downward motion corresponding to a critical compression of spring 61 the latter will exert an upward force on the snap spring 64 and cause the latter to rise, thereby effecting electric contact between the buttons 67 and 68. Under these conditions the electrodes 65 and 66 are electrically connected.

Fig. 5 shows an electric circuit which controls loom operation. This circuit includes a transformer T and a solenoid 70 having a core 71 connected to a vertical rod 72 the upper end of which is pivoted as at 73 to a knockoff latch 74 on the loom shipper handle 75. A spring 76 normally holds the latch 74 in raised position above the level of a knockoff bunter 77 on the lay 20. During normal operation of the loom the 75

bunter 77 passes under the latch 74 and the shipper handle can remain in the running position. When electrodes 65 and 66 are electrically connected as already described by depression of lever 50 the following circuit will be completed: transformer T, wire 80, contacts 65 and 66 in switch unit E, wire 81, solenoid 70, and wire 82 back to the transformer. Closure of this circuit energizes the solenoid and causes the latter to move the latch 74 downwardly against the action of spring 76 into the path of bunter 77, and as the lay advances the bunter will engage the latch 74 and rock the shipper handle 75 in a left hand direction as viewed in Fig. 5 to stop the loom.

Lever 50 normally holds the arm 47 with its bottom edge 83 extended somewhat beyond the adjacent curved edge 38 of the detector D, and when the latter is lowered to the position shown in Fig. 1 arm 47 is in position for engagement with the shuttle. If the shuttle is completely boxed as indicated in full lines in Fig. 2, it will move forwardly without touching the detector D or the arm 47 and the wall 39 will then engage the rear straight edge 85 of the detector D behind lever 45 and raise the shuttle position detector to its normal position. This normal resetting of the detector therefore does not electrically affect the switch unit E. If on the other hand the shuttle is misplaced as shown in dotted lines in Fig. 2 it will engage edge 83 of arm 47 as the lay advances and rock lever 45 before engaging edge 38 of detector D, thereby moving the lever 50 down to close the previously traced circuit. As soon as the shuttle passes the position shown for instance in Fig. 3 in its forward movement, or to the right, spring 58 acting through plunger 57 and lever 50 will restore lever 45 to its normal position relatively to the detector D. The edge 83 of arm 47 is of sufficient length to provide time for adequate energization of the solenoid 70. It will thus be seen that a resilient member such as spring 58 mounted on the detector D serves to reset the lever 45 to its normal position.

The modified form of the invention shown in Fig. 6 eliminates the lever 45 and uses a modified lever for the switch box. As shown in Fig. 6 the carrier 26 has mounted thereon a shuttle position detector finger 90 shaped somewhat similar to the detector D of the preferred form of the invention. A switch unit 91 is permanently mounted on detector 90 and has a lever 92 similar to lever 50 but curved at the lower end thereof as at 93 to have the same general contour as the under side of arm 47 of lever 45. It is not thought necessary to illustrate the interior of the switch unit 91 since the same will be substantially as already described in connection with Fig. 4. There is a spring in the switch unit 91 the same as spring 58 having the effect of holding the lever 92 in the position shown in Fig. 6 with its lower curved end located for engagement with a misplaced shuttle. When thus engaged the lever 92 will move to the right as viewed in Fig. 6 and will operate to close a contact within the switch unit 91. The latter will be connected to the wires 80 and 81 and will operate to close the circuit shown in Fig. 5 whenever lever 92 is engaged by a misplaced shuttle. After shuttle engagement lever 92 will again move rearwardly to its normal position, the spring for accomplishing this result being in unit 91 and mounted on the detector finger 90.

From the foregoing it will be seen that I have provided a shuttle position detector having an electric switch unit mounted thereon so con-

structed as to hold a shuttle engaging lever normally in shuttle engaging position relatively to the detector. The switch on the shuttle position detector is a self-contained electrical unit returning automatically to normal open position after closure by a shuttle. In both forms of the invention the lever which engages the shuttle is returned automatically to its normal position by a spring mounted on the shuttle position detector. In the preferred form of the invention a lever 45 is introduced between the misplaced shuttle and the lever 50 which is mounted on the switch unit E. In the modified form of the invention a somewhat simpler arrangement is used in which lever 45 is omitted and a lever 92 corresponding to lever 50 of the preferred form is shaped similarly to arm 47 of lever 45 for engagement with the misplaced shuttle.

Having thus described my invention it will be seen that changes and modifications may be made therein by those skilled in the art without departing from the spirit and scope of the invention and I do not wish to be limited to the details herein disclosed, but what I claim is:

1. In a shuttle position detector for a weft replenishing loom, a switch unit including a normally open electric switch mounted on said detector, means on the detector movable from the normal position thereof to effect closure of said switch, and resilient means on said detector forming part of said switch unit effective to open said switch after closure thereof.

2. A shuttle position detector for a weft replenishing loom, having mounted thereon electric contacts supported by the detector, a lever pivotally mounted with respect to the detector, and resilient means mounted on the detector normally maintaining said contacts spaced but movable to effect engagement of said contacts, said resilient means also maintaining said lever in normal position, said lever movable relatively to the detector to move said resilient means to effect engagement of said contacts and said resilient means effective thereafter to return said lever to normal position and space said contacts.

3. A shuttle position detector having mounted thereon a switch unit including a normally open electric switch, a lever pivoted on the detector, and resilient means forming part of the unit movable by the lever to close said switch and effective to open said switch.

4. A shuttle position detector having mounted thereon a switch unit including a normally open electric switch, a lever pivoted on the detector and having a given normal position relatively

to the detector, and resilient means forming part of the unit normally maintaining said switch open and said lever in normal position but movable by said lever to close said switch.

5. In a shuttle position detector for a weft replenishing loom, a switch unit including a normally open electric switch and a casing inclosing and supporting said switch and secured to the detector, a lever supported by the detector and mounted for pivotal movement relatively thereto, and resilient means within said casing normally maintaining said switch open and said lever in normal position but movable by said lever to close said switch, said resilient means thereafter opening said switch and returning said lever to normal position.

6. In a shuttle position detector for a weft replenishing loom, a switch unit including a normally open electric switch and a casing inclosing and supporting said switch and secured to the detector, a lever pivoted on said casing, resilient means within said casing normally maintaining said switch open and said lever in normal position, and a second lever pivoted to the detector and engaging the first lever and movable relatively to the detector to cause said first lever to overpower said resilient means and cause the latter to close said switch, said resilient means thereafter opening said switch and returning the first lever to normal position.

7. In a shuttle position detector for a weft replenishing loom, a switch unit including a normally open electric switch and a casing inclosing and supporting said switch and secured to the detector, a lever pivoted to said casing and having a part thereof extending beyond the outline of the detector for movement relatively to the latter by a misplaced shuttle when the lever is in normal position relatively to the detector, and resilient means within said casing normally maintaining said switch open and said lever in normal position, said lever being movable in a direction causing said part thereof to move toward said outline to cause said resilient means to close said switch.
